UNITED STATES PATENT OFFICE.

ANDERS M. STRUSHOLM, OF WOODBRIDGE, NEW JERSEY, ASSIGNOR TO
ROBERT W. LYLE, OF NEW YORK, N. Y.

DOWNDRAFT MUFFLE-KILN.

SPECIFICATION forming part of Letters Patent No. 508,063, dated November 7, 1893.

Application filed June 25, 1892. Serial No. 438,021. (No model.)

To all whom it may concern:

Be it known that I, ANDERS M. STRUSHOLM, a citizen of the United States, residing at Woodbridge, in the county of Middlesex and State of New Jersey, have invented a certain new, useful, and valuable Improvement in Downdraft Muffle-Kilns, of which the following is a full, clear, and exact description.

This invention is a round down draft muffle kiln for burning high grade clay and terra cotta articles.

Up draft muffle kilns have been constructed but they are not at all practicable on account of the great amount of fuel wasted.

The object of the down draft muffle kiln is to save fuel and at the same time to produce a higher degree of temperature within the kiln.

My invention consists in the peculiar arrangement or combination of the several parts, whereby these objects are accomplished, substantially as hereinafter described and claimed.

In the drawings hereunto annexed, Figure 1 is the ground plan of my improved round kiln. Fig. 2 is a section on line 2—2 of Fig. 1. Fig. 3 is a floor plan, and Fig. 4 is a section on line 4—4 of Fig. 3. Fig. 5 is a perspective view showing the manner of arranging the bricks in the inner or muffle wall.

This round kiln is very similar to my square down draft muffle kiln for which I filed an application on June 18, 1892, Serial No. 437,142, and in constructing my round down draft kiln, I employ a foundation of concrete or other suitable material. A central well hole is constructed in the center of the foundation and from this well leads a passage 35 to the smoke stack.

34 indicates the casing of the well hole. Four courses of fire brick 33 are laid upon the foundation and at the outer edge of this are built the furnaces 1, said furnaces having arches 15 upon which are built the kiln walls 25, of any suitable height. The walls between the furnaces are built with transverse and longitudinal air passages 2, which supply air to the furnaces and also prevent the fire brick lining 14, from being burned away. Upon the courses of brick 33 are placed the flue blocks 5, in definite positions and among these blocks is built a circular wall 6. An

arch way 7, is built over the well hole as clearly shown. The blocks 5, wall 6 and arch 7 support the kiln floor 10, 11 and it will be noticed that near the furnaces the floor is built 55 with an extra layer 12, to prevent said floor becoming too hot and being burned away.

The kiln walls 25 are provided with a lining 3, of fire brick and this lining 3 is in turn provided with a muffle-face or wall 4 which 60 serves as a muffle and also protects the fire brick lining 3 which is part of the kiln wall and cannot therefore be easily repaired when burned out, but the fire brick muffle walls 4 and 13 can be easily repaired, always keeping the walls 3 and 25 intact.

13 indicates the inner muffle wall, a sufficient space being left between the wall 4 and 13 to permit the products of combustion to ascend between them. (See Fig. 5.) An inner arched wall 22 is supported upon the inner muffle wall 13 and upon the wall 25, and upon the lining wall 3 is supported an outer arched wall 23, thus providing a crown space 75 between the two arched walls into which products of combustion pass from between the muffle walls.

24 indicates a jacket wall to prevent the radiation of heat.

Four chimneys 8 are built within the kiln 80 and extend from the floor to the lower arch helping to support said arch. These chimneys rest directly over the circular wall 6, which divides the chimney diagonally as clearly shown in Fig. 1, and upon this wall 6 85 is built within the chimney the partition wall 21. The outer sides of the chimneys are made thicker than the inner sides as they are nearer the furnace.

9 indicates a cool air passage produced in 90 the walls of the kiln adjacent to the floor to prevent the floor becoming too hot and being burned away, and similar passages 36 and 37 are arranged near the central and upper portions of the kiln respectively.

16 indicates the grate bars, 18 the bars upon which they rest and 27 a slab across the face of furnace to which the door 32 is hinged, said door being operated by the chain and weight, the same as the door of my square 100 kiln.

A cooling flue 38 is arranged above the kiln,

the same as in my square kiln and all the flues and dampers connected therewith are substantially of the same construction as those shown in my other application.

5. In operation, the articles are arranged within the kiln entrance being had through a door at one side. The door is then closed and the furnace fires started. The passages 2 aid combustion and also prevent the linings 14 10 being burned away. The products of combustion pass up between the walls 4 and 13 and also under the floor until they meet the wall 6. This wall directs it up the chimney into the crown space where they meet the products from the muffle walls and both combine and descend the other side of chimney through the arch way 7 down the center well into the smoke passage 35.

The operation of the other parts is the same 20 as in my other application and a detailed description here is unnecessary.

Having thus described my invention, what I claim is—

1. The combination with the foundation 25 having a well-hole arranged centrally thereof, of the flue-blocks supported on the foundation, the inner and outer muffle-walls having flues formed between them, and the furnaces arranged on the outside of the kiln and communicating with the said flues.

2. The combination with the foundation of

the flue-blocks supported thereon, inner and outer muffle-walls having flues formed between them, furnaces arranged within the kiln walls and communicating with the said 35 flues, and double crown-walls supported on the muffle-walls and the kiln-walls.

3. The combination with the foundation of the flue-blocks supported thereon, inner and outer muffle-walls having flues formed between them, furnaces arranged within the kiln walls and communicating with the said 40 flues, double crown-walls supported on the muffle-walls and the kiln-walls, a center well arranged below the floor of the furnace, and 45 the smoke passage.

4. In a circular down-draft muffle-kiln, the combination with the kiln-walls, of the furnaces built therein, hollow muffle-walls arranged contiguous to the kiln-walls, crown-walls supported on the kiln-walls and the muffle-walls, a floor, a center-well located below the floor, and a series of chimneys connecting the said well and the crown-space between the crown-walls, substantially as described.

In testimony whereof I affix my signature in presence of two witnesses.

ANDERS M. STRUSHOLM.
